DESIGN FOR A CONTROL INSTRUMENT

Henry Dreyfuss, New York, N. Y., assignor to
Minneapolis-Honeywell Regulator Company,
Minneapolis, Minn., a corporation of Delaware

Application June 19, 1942, Serial No. 107,245

Term of patent 14 years

To all whom it may concern:

Be it known that I, Henry Dreyfuss, a citizen of the United States, residing at New York city, in the county of New York and State of New York, have invented a new, original and ornamental Design for a Control Instrument, of which the following is a specification, reference being made to the accompanying drawing, forming part thereof, and in which

Figure 1 is a front elevation of a control instrument embodying my new design;

Figure 2 is a side elevation of the device shown in Figure 1, and

Figure 3 is a front perspective view of the device shown in Figure 1.

I claim:

The ornamental design for a control instrument, substantially as shown.

HENRY DREYFUSS.
